UNITED STATES PATENT OFFICE.

LEWIS C. WATSON AND EARL F. BOYER, OF KANSAS CITY, MISSOURI.

CONTROLLING MEANS FOR IGNITION SYSTEMS.

1,158,876.

Specification of Letters Patent.

Patented Nov. 2, 1915.

Application filed August 19, 1914. Serial No. 857,517.

To all whom it may concern:

Be it known that we, LEWIS C. WATSON and EARL F. BOYER, citizens of the United States, residing at Kansas City, in the county of Jackson and State of Missouri, have invented certain new and useful Improvements in Controlling Means for Ignition Systems, of which the following is a specification.

Our invention relates to time controlling means for ignition systems embodying magnetos, and the invention is especially adapted for use in the ignition systems of motors employed for propelling automobiles, motor boats, and the like.

15 The primary object of the invention is to provide means whereby the time of firing of explosive charges in the cylinders of a motor may be advanced or retarded at will without varying the intensity of the igniting sparks.

20 We attain the foregoing object by having the sparks always occur at such times when the armature core is at a predetermined distance from the pole-shoes of the field of the magneto as to produce sparks of maximum intensity.

25 In order that the invention may be fully understood, reference will now be made to the accompanying drawings, in which:

Figure 1 is a diagram of a motor, its ignition system, and our invention. Fig. 2 is a longitudinal section of the important features of the invention connected to the spindle of an armature. Fig. 3 is a vertical cross section, enlarged, on line III—III of Fig. 5. Fig. 4 is a side elevation of the invention mounted upon the spindle of a magneto. Fig. 5 is an elevation, partly broken away, of a section of important parts of the invention. Fig. 6 is a cross section of 40 a part of the magneto, showing the relative position of its armature core to the pole shoes of the field at the time the spark occurs. Fig. 7 is a broken elevation of the contact breaker of the magneto.

45 A designates the motor, B the magneto, and C the wiring between said magneto, the motor, and the spark plugs C'.

D designates the gears whereby the magneto armature E is driven from the motor, 50 F the armature spindle, G the contact breaker disk secured to one end of the spindle F, H a contact screw rotatable with the disk G, I another contact screw normally engaging the screw H, J a bell-crank lever carrying the screw I, K a spring bearing 55 against the lever J to hold the screw I in

engagement with the screw H, and L the fixed segments for rocking the lever J to throw the screw I out of engagement with the screw H twice at each revolution of the 60 disk G to short circuit and interrupt the primary current of the magneto, so that sparks will occur at the spark plug C'.

The magneto B is, preferably, of the non-variable timing type, or one in which the 65 breaker-box M is nonrockable. This insures sparks of maximum intensity, as the screw I is not disengaged from the screw H until gaps N, of such length as to insure sparks of maximum intensity, occur between the 70 armature E and the pole shoes C, Figs. 6 and 7. The foregoing magneto is one of ordinary type.

Our invention comprises means whereby the armature E may be retarded or advanced 75 at will relative to the motor pistons, to obtain any desired compression of the charges in the cylinders without varying the length of the gaps N at the time of firing said charges. By thus having the gaps N of a 80 uniform length best adapted for the production of the hottest possible sparks at the spark plugs C', it is obvious that greater efficiency is had than where the gaps are frequently so great that the sparks produced 85 are often too weak to ignite the charges, as is the case where magnetos of the ordinary variable timing type are employed, especially when the latter are adjusted to fully retard the time of firing. 90

In carrying out the invention, we employ a coupling 1 embodying a bushing 2 firmly mounted upon the armature spindle F, and a sleeve 3 loosely mounted upon said bushing 2. The sleeve 3 is free to rotate upon the 95 bushing 2, but is held from longitudinal movement thereon by a collar 4 integral with one end of the bushing, and a nut 5 threaded upon the opposite end of said bushing 2. Collar 4 fits into an annular internal recess 100 4^a in the adjacent end of the sleeve 3, Figs. 2 and 5.

Bushing 2 has a pair of oppositely-disposed longitudinal grooves 6 in its periphery to receive the inner ends of a pair of 105 lugs 7, extending through oblique slots 8, in the periphery of the sleeve 3. The outer ends of the lugs 7 are fixed to a shifting member 9 comprising an inner ring 10 loosely embracing the sleeve 3, and an outer 110 slip-ring 11 loosely embracing said inner ring 10. Antifriction balls 12 are inter-

posed between the inner and outer rings, so that the rotation of the former within the latter will be attended with but little friction. The slip-ring 11 is provided with a 5 pair of diametrically-opposed trunnions 13 fitting into the slotted ends of a yoke 14, mounted upon a rock-shaft 15 which may be actuated at a distance, such as the seat of an automobile, by a rod 16 when the invention is applied to the ignition system of 10 an automobile.

The coupling member 1 may be connected to the motor in any suitable manner. In the drawings we have shown the sleeve 3 15 provided at one end with a peripheral shoulder 17, having two diametrically-opposed grooves 18 to receive corresponding lugs 19 on a member 20, fixed to an intermediate shaft 21 carrying one of the 20 gears D.

In practice, the time of firing the combustible charges in the cylinders can be varied with relation to the position of the pistons in said cylinders by actuating the 25 rod 16 to cause the shifting member 9 to move either to the right or the left, as required. For instance, when the firing is to be retarded to permit the pistons to reach the ends or other predetermined point, of 30 their compression strokes, the shifting member 9 is moved to the right. As the sleeve 3 is held by the member 20 from rotating independently of the intermediate shaft 21, the lugs 7, moving in the oblique slots 8. 35 and the straight slots 6, turn the bushing 2 backward and thereby retard the armature E, so that it will not reach the firing position (Fig. 6) until the pistons have advanced to the predetermined point of their 40 compression strokes. When the firing is to be advanced the member 9 is shifted to the left, so that the armature E will reach the firing position earlier in the compression

strokes of the pistons. In both cases the 45 gaps N will be of a uniform length to produce the hottest possible sparks at the spark-plugs C', because the position of the segments L is never changed, whereas in magneto's of the variable timing type embodying rocking segments, the gaps N vary to 50 such an extent that efficient sparks are produced only when advanced as fully as possible.

Having thus described our invention, 55 what we claim and desire to secure by Letters Patent, is:

In a device of the class described, a shaft, a rotatable bushing having one end fixed thereto, a collar carried by one end of the bushing, a rotatable sleeve encircling the 60 bushing and having one end engaged with said collar, a nut engaged with the other end of the bushing and sleeve to hold the sleeve and bushing against relative longitudinal movement, said sleeve having oppositely disposed oblique slots formed therein, said bushing having longitudinal grooves formed therein and in registry with the slots, a sectional ring encircling the sleeve, the inner ring section having a pair of diametrically disposed pins engaged in said 65 slots and grooves, means carried by the outer ring section for shifting the sectional ring longitudinally of the sleeve simultaneously with the rotation of the inner ring section, a driving shaft alined with the first 70 named shaft, and means for locking the driving shaft to said sleeve.

In testimony whereof we affix our signatures, in the presence of two witnesses.

LEWIS C. WATSON.
EARL F. BOYER.
